US00D971764S

(12) **United States Design Patent** (10) Patent No.: **US D971,764 S**
Wännerud (45) Date of Patent: **** Dec. 6, 2022**

(54) **RADIATION AND GAS DETECTOR**

(71) Applicant: **Radonova Laboratories AB**, Uppsala (SE)

D839,117 S * 1/2019 Hirose D10/81
D884,521 S * 5/2020 Mou D10/81

* cited by examiner

(72) Inventor: **Oscar Wännerud**, Storvreta (SE)

Primary Examiner — Antoine Duval Davis

(**) Term: **15 Years**

(21) Appl. No.: **35/512,809**

(57) **CLAIM**

(22) Filed: **Apr. 28, 2021**

The ornamental design for a radiation and gas detector, as shown and described.

(80) **Hague Agreement Data**

Int. Filing Date: **Apr. 28, 2021**

DESCRIPTION

Int. Reg. No.: **DM/214271**

1. Radiation and gas detector

Int. Reg. Date: **Apr. 28, 2021**

2. Radiation and gas detector

Int. Reg. Pub. Date: **Oct. 29, 2021**
